ATTORNEY

UNITED STATES PATENT OFFICE.

LOUIS C. GERKEN, OF NEW YORK, N. Y.

WASHING-RUBBER.

SPECIFICATION forming part of Letters Patent No. 685,041, dated October 22, 1901.

Application filed July 31, 1901. Serial No. 70,334. (No model.)

To all whom it may concern:

Be it known that I, LOUIS C. GERKEN, a citizen of the United States, and a resident of New York, in the county of New York and State 5 of New York, have made and invented certain new and useful Improvements in Washing-Rubbers, of which the following is a specification.

My invention relates to an improvement in 10 washing-rubbers employed in connection with bottle-washing machines—such, for instance, as shown and described in Letters Patent No. 329,390, dated October 27, 1885, and granted to J. M. and W. G. Hoyt—the object being 15 to provide a device of this kind which shall retain all the advantages possessed by articles of a like character and which at the same time shall be so constructed that its 20 wearing and lasting qualities will be greatly enhanced.

With these and other ends in view my invention consists in certain novel features hereinafter described, and pointed out in the claims.

25 In the accompanying drawings, Figure 1 is a perspective view of my improved washing-rubber. Fig. 2 is a horizontal sectional view of the same, taken on the line 2 2 of Fig. 1. Fig. 3 is a vertical sectional view taken on 30 the line 3 3 of Fig. 1.

As is well known to the users of these washing-rubbers, rubber has proved to be the best material out of which to manufacture the washers, principally because of its yielding and cleansing qualities. The great objection, however, urged against these washing-rubbers is the fact that they last but a short while, the average length of life of one of the rubbers being from three to five hours, 35 after which they become unfit for further use and are thrown away or discarded. After repeated experiments I have found that these washers may be greatly improved by the addition of cloth or fabric to the rubber, the fabric being so arranged or combined with the latter that it will present its edge or edges to the wearing side or sides of the article in that while the elasticity is retained its life at the same time will be materially increased or 40 lengthened.

Referring to the drawings, A represents the washer, consisting of the two arms B C, preferably joined together by the connecting web or strip D. These arms are molded or formed with recesses a, into which fit the springs of 55 the bottle-washer—such, for instance, as those shown in Design Letters Patent granted to me October 25, 1898, and numbered 29,540. Within these arms, and preferably molded therein, are the strips of cloth or fabric b, 60 one above and one below the opening a, the strips of fabric being so placed or arranged that the edges thereof will be presented to the outer sides or surfaces of the arms, which surfaces come in contact with the inner surface 65 of the bottle during the washing or cleasing operation.

It will of course be understood that while I prefer to use two strips or pieces of cloth or fabric in each of the arms B C one strip 70 or piece only may be employed, the article, however, being much more effective when two or more are used by reason of the fact that the washers oftentimes wear unevenly.

Having fully described my invention, what 75 I claim as new, and desire to secure by Letters Patent, is—

1. A washing-rubber of the character described, consisting of two arms joined together and made of rubber, and containing 80 cloth or fabric, the latter being so placed or arranged as to present its edge to the wearing-surface of the article, substantially as described.

2. A washing-rubber of the character de- 85 scribed, consisting of two arms joined together, and made of rubber, each of said arms being provided with a hole or opening, and strips of cloth or fabric contained in each of said arms and above and below said openings, 90 said cloth being so arranged as to present its edges to the wearing-surfaces of the article, substantially as described.

Signed at New York, in the county of New York and State of New York, this 29th day 95 of July, A. D. 1901.

LOUIS C. GERKEN.
